UNITED STATES PATENT OFFICE

WILLIAM M. BRUCE, OF SPRINGFIELD, OHIO

ATTACHMENT FOR WIRELESS RECEIVERS

Application filed June 22, 1927. Serial No. 200,608.

My invention relates to an attachment for wireless receivers and has for its object to provide means for tuning the plate circuit of any desired thermionic tube of a receiving set in which provision is not made for such tuning.

In its preferred form it consists of a tuning device and a connector which can be inserted between a thermionic tube and its socket in such a manner that the tuning device will be looped in the plate circuit of said tube while the other circuits such as the filament and grid will be unchanged.

In the accompanying drawings in which like parts are represented by similar letters of reference:

Fig. 1 is a diagrammatic view illustrating my invention and showing the circuits embodying my improved tuning device.

Fig. 2 is a perspective view of a thermionic tube and its socket to which the connector is attached.

Fig. 3 is a perspective view of the tube and connector removed from the tube socket.

Fig. 4 and Fig. 5 are detail views of the connector.

Fig. 6 is a sectional view showing a modification.

In the drawing, *a* represents the ordinary receiving socket of a three element thermionic tube *b*; *c* is the connector adapted to be inserted between the tube socket *a* and the thermionic tube *b*; *d* is a suitable tuning mechanism which is connected to the terminals of the connector *c* so that when the parts are in place as illustrated in the several views the tuning device will be looped in the plate circuit of the tube, particularly as shown diagrammatically in Fig. 1. The tuning device which may be of any well known form either in the nature of variable inductances or variable capacities is preferably enclosed in a separate casing as indicated by dotted lines in Fig. 1 and connected by suitable flexible connections or cord to the terminals of the connector.

The preferred form of the connector as illustrated in Figs. 3, 4 and 5 consists of a plate or disk *c1* of thin insulating material such as hard rubber or fibre and it is pierced

with four openings of different diameters to receive the well known tube terminals 1, 2, 3 and 4. This plate or disk *c1* will be preferably constructed of substantially the same size or diameter and shape as the base of the tube *b* so that when slipped into place over the tube terminals 1, 2, 3 and 4 it will form a slight extension of the tube base.

The plate *c1* is provided on one side with two contacting devices *c2* and *c3*. The one *c2* is provided at its lower end with a laterally projecting part *c4* which projects across the end of the tube terminal 2, which is the terminal for the plate circuit, and it is provided on one side with an insulated strip *c5* which lies across the tube 2 with the other side of the projection *c4* of conducting material exposed.

The other contacting device *c3* is preferably in the nature of flexible metallic strips which when connected and assembled in place at the bottom of the tube will contact on a side or sides of the plate terminal 2.

From the contacts *c2* and *c3* are terminals *c6* and *c7* which extend from these contacts *c2* and *c3* to a point above the socket *a* when the tube is in place and preferably above the base portion of the tube *b* particularly if the same is made of metal. These terminals *c6* and *c7* are made of thin strips of metal such as copper and preferably insulated for a distance sufficient to pass beyond the base of the tube when the connector is in place and this may be accomplished by enameling that portion of the strips or in any other desired way.

With the connector in place on the tube it will be inserted in the socket in the usual way; the different sizes of tube terminals securing the proper relative position of the parts to insure the desired connection. The terminals 1, 3 and 4 will contact with the socket terminals in the usual way. The terminal 2, however, for the plate circuit by reason of the projecting portion *c4* of the contact *c2* will not make contact with its socket terminal, but the contact *c2* will make connection with said terminal and inasmuch as the terminal 2 is in electrical connection with the contact *c3* it will be seen that the terminal *c6* is electrically connected to the socket terminal of the plate

circuit and the terminal c_6 is electrically connected to the tube terminal of the plate.

To complete the circuit the tuning device d by means of suitable electrical connection preferably in the form of flexible cords is attached as indicated in Fig. 1 to the terminals c_6 and c_7 so that the tuning device d is looped into the plate circuit and furnishes means for tuning the plate circuit of any tube to which the connector may be applied.

Fig. 6 shows a modified form of connector in which an auxiliary socket c_8 is provided preferably of insulating material. This auxiliary socket has four terminals, only two, 5 and 6, being shown in this drawing. All of these terminals on the auxiliary socket with the exception of that corresponding to the tube terminal 2 will be provided with contacts c_9 which engage the tube terminals and establishes a connection between said tube terminal (when it is in place) and the auxiliary socket terminal. The socket terminal 5 corresponding to the tube terminal 2 is connected to a lead c_{10} which extends to the outside of the auxiliary socket and a contact c_{11} on the interior of the auxiliary socket by a lead c_{12} which extends to the outside of the auxiliary socket and this contact c_{11} is adapted to make electrical connection with the plate terminal 2 when the tube is in place. It will be understood that the leads from the tuning device d will in this case be continuations of leads c_{10} and c_{12} .

In establishing the connection with this form of connector a tube is removed and the auxiliary socket is placed into the regular tube socket after which the tube is inserted in the connector socket the upper plate c_{13} of said auxiliary socket being provided with 35 perforations to receive the usual tube terminals; the tuning device will be looped into the plate circuit of the tube by means of the contact c_{11} engaging the tube terminals 2 and the lead c_{10} which extends to the auxiliary socket terminal 5.

This device is applicable to any of the usual receiving sets (except the so-called super-heterodyne circuit) in which no provision is made for tuning the plate circuit and when 50 so applied the amplification of the set may be increased many fold particularly when distant stations or low-powered stations are being received and from which the signals are with difficulty being obtained.

The tuning device may be connected to the plate circuit of any of the tubes, either detector or of radio amplification and will amplify signals received on the set very materially and if the tuning device is applied 55 to the detector tube or a tube forming the second or third stage of amplification the danger of disturbances from tube squeals caused by the oscillations of the tube in tuning the plate circuit will be obviated.

75 A simple form of tuning which I have used

successfully consists of a coil d_1 , a contact d_2 pivoted at d_3 and provided with a handle d_4 and a pointer or index hand d_5 moving over a graduated scale d_6 . When in the zero position this tuning device will have no effect on the incoming signals, but as the hand d_4 is moved along the scale a greater or less number of turns of the coil d_1 are included in the plate circuit, thus tuning the plate circuit to the incoming signals.

Having thus described my invention, I claim:

A connector for thermionic tubes embodying a disk of insulating material whose outer periphery is approximately coextensive with the base of the tube and having perforations to receive the legs of the tube, a contacting device adjacent one of the perforations and adapted to engage with the tube leg which projects therethrough and a separate contacting device connected to the under side of the disk and having an offset portion which projects in line with the axis of the opening through which the leg extends and below the contacting device adapted to engage said leg, 80 said offset contacting device being insulated on its upper side to prevent electrical contacts with the projecting tube leg and two independent thin metallic strips connected to the respective contacting devices and around the periphery of the disk and adapted to project upwardly along the base of the tube and between said base and the tube socket, said metallic strips being insulated.

In testimony whereof, I have hereunto set 100 my hand this 2nd day of March, 1927.

WILLIAM M. BRUCE.
